DIRECT CURRENT AMPLIFIER

David G. C. Luck, Haddon Heights, N. J., assignor to Radio Corporation of America, a corporation of Delaware

Application August 14, 1937, Serial No. 159,025

3 Claims. (Cl. 179—171)

The present invention relates to a direct current amplifier embodying a plurality of electric discharge amplifier tubes responsive to an applied direct current variation at the input circuit to 5 provide a corresponding change in the output voltage or current.

It is an object of the present invention to provide an amplifier to which an alternating potential may be applied and controlled by a direct 10 voltage of relatively low value whereby, in effect, amplification of the direct control voltage by an alternating current amplifier is permitted, thereby avoiding the instability common to direct current amplifiers.

15 It is also an object of the present invention to provide an electric discharge tube amplifier responsive to relatively small variations in a direct voltage applied thereto to control an alternating current in phase and magnitude, whereby the 20 amplifier may be utilized for the control of the operation of alternating current motors and the like.

Other objects and advantages of the invention will be apparent from the following description 25 when considered in connection with the accompanying drawings in which

Figure 1 is a schematic circuit diagram of an amplifier embodying the invention, and

Figures 2 and 3 are similar schematic circuit 30 diagrams of modifications of the circuit of Fig. 1.

Referring to Fig. 1, a detector stage 5, utilized as a source of controlling potential, is provided with input leads 6 and 7 connected respectively with the control grid 8 and the grounded cathode 35 9 of the tube 5. The output anode 10 is connected through a series output resistor 11 with a positive anode potential supply lead 12. The anode is also connected to ground through a suitable filter capacitor 13. Signals other than direct current variations are taken from the anode through a series resistor 14 and output coupling capacitor 15 for any suitable utilization device (not shown).

The detector stage 5 is primarily utilized in controlling a main direct current amplifier included within the dash line rectangle 16 and comprising at the input end a pair of pentode electric discharge amplifier devices 17 and 18, each having a cathode 19, a control grid 20a or 20b, a screen grid 21, a suppressor grid 22 and an 45 output anode 23.

The control grid 20a is connected to the control potential source and is biased to a degree controlled by the resistor 39. The control grid 20b is grounded. The output anodes are connected in push-pull or balanced relation to each

other and coupled to a pair of balanced or push-pull amplifier tubes 25 and 26.

On the input side, the control grid 20a of the tube 17 is connected through a series isolating resistor 27 with a variable source of negative biasing potential comprising the movable contact 28 of a resistor element 29 connected across a battery or other suitable direct current potential source 31 interposed in the output circuit of the detector 5. An input terminal 32 is connected 10 with the ground lead 7, with the cathode 9 of the detector and with the cathodes 19 of the amplifier devices 17 and 18 through a self bias resistor 39. The control grid 20b of the amplifier 15 tube 18 is also connected to the ground lead 7 through a lead 40 and the control grid 20a of the amplifier tube 17 is grounded through a by-pass capacitor 41.

It will, therefore, be seen that both control grids of the balanced amplifiers 17 and 18 may 20 receive the same biasing potential, the tube 18 receiving the bias directly from ground, the tube 17 receiving the bias through the input circuit 38—36—31—29—27. The connection for the grid 20a of the amplifier tube 17 is directly through a 25 conductive connection with the anode 10 of the stage 5 and is, therefore, subjected to the anode potential. This connection is provided to permit adjustment of the value of the unidirectional control across leads 36—33 to a value for which 30 zero output is desired. This biasing arrangement permits the biasing potential on the two tubes to be equalized by adjusting the biasing potential on the tube 17 with respect to the fixed biasing potential on the tube 18.

The suppressor grids 22 are connected to the cathodes 19. The output anodes 23 are coupled to the tubes 25 and 26 by a balanced or push-pull coupling means admitting of relatively high gain. In the present example, this coupling means is 40 of the impedance or resistance coupling type comprising anode coupling resistors 42 connected in balanced relation to the output anodes 23 and having a common anode potential supply lead 43 which receives positive anode operating potential from a positive supply lead 44 through a series voltage reducing resistor 45. A suitable by-pass capacitor 46 is provided for the lead 43 to ground 7. The grids of the tubes 25 and 26, indicated at 47 and 48, respectively, are coupled 45 to the output resistors 42 through coupling capacitors 49, which are connected to grid resistors 50 having a common return lead 51 to ground and to the cathodes 52 through a self bias resistor 53. The tubes 25 receive anode potential from 55

the anode supply 44 through a series resistor 54, a common supply lead 55 and the push-pull or balanced primary 56 of a coupling transformer 57 to which primary winding the anodes 58 are connected.

5 The transformer 57 is provided with a push-pull or balanced secondary winding 59 to which the grids 60 of a pair of power amplifier tubes 61 and 62 are connected in balanced or push-pull relation. The tubes 61 and 62 are also provided with a balanced or push-pull output transformer 63 having a balanced primary winding 64 connected with the anodes 65 and with the positive potential supply lead 44 through a common lead 66. Each half of the primary winding is provided with a spark gap indicated at 67 for preventing excessive potential surges across the primary winding. The input secondary winding is connected at the center tap 68 directly with the 10 cathodes 69 and the ground lead 7, the latter connection being indicated by the lead 70, this connection being made through capacitors 69a and 69b for the purpose of suppressing interference from a motor 73 which is controlled 15 through the circuits previously described.

20 The secondary 71 of the output transformer 63 is provided with output leads 72 connected with the armature of the alternating current motor 73 which is provided with a field winding 30 74 connected through supply leads 75 and a phase controlling capacitor 76 and resistor 77 with an alternating current supply source indicated by the leads 78. The supply leads 78 are isolated from the motor leads 75 by an isolating transformer 79 which may step up or step down the alternating voltage as may be required for the motor winding 74, the proper phase being determined by the capacitor 76 and resistor 77.

35 Alternating current energy from the secondary winding of the isolating transformer is applied to the motor element 73 to operate it in either direction. Thus, alternating current energy is applied to the balanced control stage of the amplifier comprising the tubes 17 and 18 on the screen grids 21 through a supply lead 80 which 40 is connected to the alternating current transformer 79 to derive a suitable potential therefrom with respect to the cathode return or ground lead 7 which is extended to connect with one side of the alternating current secondary, as indicated at 81. A predetermined potential is derived with respect to the terminal 81, for the lead 80, by a suitable tap 82 on a potentiometer resistor 83 connected across the secondary of 45 the transformer 79, thereby applying the alternating potential existing between the tap 82 and the terminal 81 across a portion of the resistor 83, between the ground lead 7 or cathode return and the screen grids 21. This potential is so 50 chosen that when applied through the successive amplifier stages it results in a normal operating voltage at the output leads 72 for the full operation of the motor.

55 The alternating current is thus introduced or coupled electronically to the push-pull or balanced amplifier channel at the input or control stage, the input or control grids of which are normally balanced to provide zero output. The control grids 20 of the control stage are normally biased to a region of considerable curvature of the tube characteristics. The direct control voltage from the control potentiometer 28-29 is applied to the one control grid. For one control 60 voltage value corresponding to the fixed bias pro-

vided on the control grid 20b of the tube 18, the tubes are thus balanced and no output occurs.

65 If the control potential is now varied in a positive or negative direction, the potential on the control grid of the tube 17 will increase or decrease with respect to the voltage on the control grid of the static tube 18, thereby causing the gain of the tube 17 to decrease with increased negative bias and to increase with decreased negative bias with respect to the gain 10 of the static tube 18 and thereby causing the alternating potential to be amplified in the amplifier stage 25-26 and in the power output stage 61-62 and to be applied through the leads 72 to the motor element 73. Departure from the 15 balanced condition of the control stage thus produces a control potential which is utilized to produce an output voltage corresponding to the direction of departure from balance as one half or the other of the balanced amplifier channel 20 is caused to have the higher gain. With this arrangement, the alternating current motor 73-74 may be caused to operate in either direction with increasing power or speed as the contact 28 of the control potentiometer is adjusted in either 25 direction from the condition of balance or as the control potential causes the condition of balance to be varied in either direction on the control amplifier 17.

30 Sudden or abrupt changes in potential producing a transient voltage wave of any appreciable magnitude are reduced by the filter 27-41. However, as a precaution against surges, the power amplifier is provided with the flash-over gap across each half of the output transformer 35 primary as hereinbefore described.

35 The amplifier output stage must be capable of transmitting the required amount of power for operation of the motor. The preceding stage or stages represented by the voltage amplifier stage 40 25-26 must be capable of providing sufficient gain for operating the power output stage and the input or control stage must be adapted to provide a push-pull or balanced output with a parallel connected input circuit for the control 45 grids whereby the input amplifiers or control stage may be brought to a condition of static balance so that the control potential may be effective to control the operation of the motor as previously indicated. The control source driving the balanced input stage must, of course, provide a sufficiently wide range of control potential to increase the biasing potential on the control tube 17 to provide full gain through one-half of the amplifier channel and to decrease the 50 biasing potential sufficiently to provide full gain through the opposite half of the amplifier channel whereby the motor is caused to operate with predetermined power rating and speed in either direction.

60 The system of Fig. 2 is similar to that of Fig. 1 in some respects, but differs therefrom in that the alternating voltage is applied to a pair of control grids instead of the screen grids as in Fig. 1. Zero output of the control tubes 17-18 is 65 established by means of a bias potential source 90 across which is connected a resistor 91 for biasing the control grid of the device 17 and a resistor 92 for biasing the control grid of the device 18. With these connections, the potentiometer 91 is 70 adjusted for operation on the most curved part of the tube characteristic with the normal value of direct current input, and the potentiometer 92 is adjusted to produce zero alternating current output for normal direct current input. The 75

operation of this system is substantially the same as that of Fig. 1.

The system of Fig. 3 differs from that of Fig. 1 in that the alternating current is introduced into the plate circuit of the control tubes 93 and 94. This system, like those previously described operates to control the alternating current output in response to variation in the unidirectional input or control voltage.

From the foregoing description, it will be seen that through the medium of a balanced direct current control stage having the input grids connected in parallel and the output anodes connected in push-pull relation, a relatively low alternating current potential may be introduced electronically into the control stage on the screen grids of a pair of pentodes constituting such stage and that relatively small variations in direct controlling potential may be caused to provide effective control of the alternating current output of the amplifier channel, both in magnitude and in phase, thereby to provide an alternating current control potential adapted to operate alternating current apparatus such as motors and the like at controllable levels and in either direction.

I claim as my invention:

1. A direct current controlled alternating current amplifier including a pair of electron discharge devices provided with push-pull connected output circuits and with parallel connected pairs of input circuits, means for applying alternating potential to one of said pairs of input circuits, means for applying a unidirectional control potential to one of the other pair of said input cir-

cuits, and means for adjusting said unidirectional control potential to a predetermined value at which no alternating current is produced in said output circuits whereby variations of said control potential from said value varies the alternating current delivered from said output circuits. 5

2. In the operation of a direct current controlled alternating current amplifier including a pair of electron discharge devices provided with push-pull connected output circuits and with 10 pairs of parallel connected input circuits, the method which comprises applying alternating potential to one of said input circuit pairs, and applying to one input circuit of said other pair a unidirectional control potential and adjusting 15 said unidirectional control potential to a normal value at which no alternating current is produced in said output circuit, whereby variations of said control potential from said value in opposite directions reverses the phase of the alternating current delivered from said output circuit. 20

3. The combination of a pair of electron discharge devices provided with push-pull connected output circuits and with a plurality of input grid circuits, means including an alternating current 25 connection to two of said grid circuits in parallel for producing alternating current in said output circuits, means for applying bias potentials to another of said input circuits, and means for applying to one of said input circuits a unidirectional control potential whereby the alternating current delivered from said output circuits may be controlled as to phase and level. 30
